Spinning Mach.

Patented Apr 1, 1830.

Inventor
C. Danforth

A. G. 1839

Charles Darnforth, Inventor, of Paterson, New Jersey
by his Attorney.

The undersigned, to witness certain facts, and to give his certificate of the same, testifying and affirming in the words of the said Charles Darnforth, his self of his improvement in the Spinning machine, commonly known by the name of Darnforth's Patent Thimble.

Whereas these presents shall come, to be it known that Charles Darnforth of Paterson in the County of Essex and State of New Jersey have invented a new and useful improvement on a spinning machine for spinning Cotton commonly known by the name of Darnforth's Patent Thimble, for which Thimble I obtained Letters Patent September 25th A.D. One thousand Eight hundred and twenty eight, under the name of the Changeable Fly, and that the following is a full and exact description of the said improvement as invented by me. It consists of an improvement by which the cylinder made use of for driving the valves by rotation instead of revolving on fixed stationary bearings, is made to traverse with the frame rails & rollers, whereby the tension of the bands is kept the same when the rails are up, in the centre or at the bottom. It also consists in dropping or lowering the valve and Bobbin for the convenience of piecing or mending the broken ends or threads. This invention or improvement I call the traversing cylinder and drop bobbin. The cylinder is made to traverse by the same apparatus which gives motion to the rails, instead of having the cylinder bearings fastened to the ends of the frame as is the case on the ordinary Thimble. There is a bar of cast iron running across the frame from one transom rail to the other, the ends of this bar are bolted fast to a flange on the end of the transom rails. There is a bar of this kind at each end of the transom rails, in the centre of which bars the bearing of the journals of the cylinder are fixed so that as the rails rise and fall the cylinder rises and falls with them. The dimensions for driving or turning the cylinder is as following, viz. There is a shaft or hollow cylinder made long by one and one half inch diameter, compared to having a flat iron bar at the front of the frame which makes from the centre of the frame and about one inch from the centre of the cylinder

when the cylinder goes up, our machine goes up, and when the cylinder goes down, the counter shaft goes down. The counter shaft is made of the same metal as the cylinder, to which shaft a frame of four iron bars are made in an angle of 90°, so that the distance between any of a side sufficient to prevent the stops of the belt from springing into them; at the top of these stands are fixed bearings for a counter driving shaft. This shaft it will be seen runs parallel with the cylinder and is, in a line with it when the cylinder as before stated, is in the center. On the one of this counter shaft are the feet and loose pulleys by which motion is communicated to the whole machine, and on the other is a pulley that gives motion to the cylinder by a belt running from said pulley, round a pulley on the end of the cylinder. The rollers are turned by this same counter shaft by means of a belt or gear. There is a connecting or piston rod, running from the cylinder, joined to the journal of this counter shaft, having a hub on each end these hubs are perforated and drilled thus whisks the journal of the cylinder and the journal of the counter shaft paper. These hubs serve as a bearing for the cylinder journal at one end, and for a bearing for the end of the counter shaft. The inside surfaces of these hubs are turned and ground out to suit a socket, and a cap box in the cap bar and on one of the stands above written of. The use of this connecting or piston rod is to steady the counter driving shaft and to keep it always the same distance from the cylinder, so that the cylinder belt will be of the same tightness when the bars are up as when the bars are down. The apparatus for dropping the weights and bolts is as follows, fig. The traverse rails instead of running on the spindle or having the spindle pass through them (as is the case with the ordinary hand) are placed about three inches back of the spindle. The rails are made of cast iron about three inches wide, and about a quarter of an inch thick having a rib or stiffener on the back side about one inch deep, on the front is a rib about one sixteenth of an inch deep for the bars to rest upon, when it is to rest against. The bars are made of rolled iron about three quarters of an inch wide and about one eighth of an inch in thickness. They are long enough to extend from the back rail or stiffener on the one end, about half a yard to the front of the spindle. They are placed so as to run parallel to one

and a piece of leather about one and one quarter of an inch
long, having three or four small holes made in it near the am-
tus of the lever made for the purpose. On this bolt is a spiral spring made
of about number eighteen wire about one and half inch long. This spring
is regulated by a nut secured on the bottom of said bolt. The use of this
spring is to keep the lever held up against the lower side of the walls.
There is a slot made thro' the front and of the lever, this slot the spin-
ner, and the valves which run in the spindle rest on this lever and of
course increase with the lever and easily, when it is made broken, this
lever is freed from the spiral spring enabling when the end being at-
tached to the lever is let go, it occurs to it to place and the end is picked
up. The same effect of dropping the bobbin is done by means of a weight and
lever, that is done with a spring. What I claim as my invention is the
turning of the cylinder with the walls, and the dropping the bobbin
for the convenience of opening in all and every manner whatever on the
above mentioned.
